MACHINE FOR OPERATING UPON SOLES

Fred. Ricks and John William Pratt, Leicester, England, assignors to United Shoe Machinery Corporation, Borough of Flemington, N. J., a corporation of New Jersey

Application March 24, 1942, Serial No. 435,992
In Great Britain April 29, 1941

8 Claims. (Cl. 12—27)

This invention relates to machines for operating upon soles and is herein illustrated and described as embodied in a channeling machine of the type described in U. S. Letters Patent No. 1,023,801, granted April 23, 1912 upon the application of Frederic E. Bertrand. In machines of this type the sole is presented upon a work table which is normally held in a raised operating position and which may be lowered by a treadle to accommodate the removal of the sole from the machine and the presentation of a new sole to be operated upon. Such machines, furthermore, are provided with an edge gage which may be shifted transversely of the direction of the feed to vary the locality of operation of the channeling knives with reference to the edge of the sole. The edge gage shifting mechanism disclosed in Letters Patent No. 1,023,801 is operated by hand. An improvement upon this mechanism, however, is disclosed in U. S. Letters Patent No. 2,241,523, granted May 13, 1941, upon the joint application of Fred Ricks and Frank Coleman Choice, such improvement comprising a power driven mechanism under control of the operator for shifting the edge gage from one operating position to another.

It is an object of the present invention to provide an edge gage shifting mechanism more fully automatic in character and at the same time of simpler construction than that disclosed in Letters Patent No. 2,241,523. In accordance with a feature of the present invention, the edge gage shifting mechanism is automatically returned to its initial position by the lowering of the work table to accommodate the removal of a sole from and the presentation of a new sole to the operating instrumentalities of the machine. In accordance with a further feature, the machine illustrated herein is provided with a cam which not only controls the movements of the edge gage but which also itself determines the number of stop positions of the cam. This cam is one of a series of readily replaceable cams designed to shift the edge gauge greater or less distances according to the type of work desired and to select one or more stop positions among the total number of stop positions provided by the mechanism. With the above and other objects in view the invention will now be described with respect to the following drawings and will thereafter be pointed out in claims.

In the drawings,

Fig. 1 is a side elevation of a portion of a channeling machine provided with the improved mechanism;

Fig. 2 is a plan view of some of the parts shown in Fig. 1 including the edge gauge and the operating members directly associated therewith;

Fig. 3 is an end elevation of part of the improved mechanism;

Fig. 4 is a sectional side elevation on the line IV—IV in Fig. 3;

Fig. 5 is a detail view, partly in section, of a latch arm shown in Fig. 4; and

Fig. 6 is a sectional view taken on the line VI—VI of Fig. 3.

The illustrated machine is provided with an edge gage 1 (Figs. 1 and 2) against which the edge face of an insole is held by an operator as the insole is fed through the machine and is operated upon by the channeling knives. The improved mechanism illustrated herein consists of a power operated device controlled by the operator for moving the edge gage transversely of the direction of feed of the work at various times during the operation to cause the channeling to be performed at different distances from the edge of the insole. This mechanism has a bell-crank lever 3 which is pivotally mounted on an eccentric 7 carried by the upper end of a vertical shaft 9 rotatably mounted for adjustment in the frame of the machine. The lever 3 has an arm 5 upon the free end of which are formed gear teeth which mesh with rack teeth on a slide upon which the edge gage is carried. The edge gage 1, the arm 5 and the above-mentioned slide are similar to corresponding elements of the machine disclosed in Letters Patent No. 1,023,801 already referred to. The purpose of the eccentric 7 is to provide an adjustment to bring the gear and rack teeth accurately into engagement. The bell-crank lever 3 has another arm 11 which is pivotally connected by a universal coupling 300 to one end of a substantially horizontal link 13. The opposite end of the link 13 is pivotally connected by a universal coupling comprising a pin 14 to the upper end of a cam lever 15 (Fig. 3). A horizontal stud 17 secured in a bracket 19 which is mounted upon the frame of the machine provides a fulcrum for the cam lever about midway between the ends of the lever. The pin 14 is rotatably mounted in the lever 15 to provide an initial adjustment of the edge gage, the portion of the pin which engages the link being eccentric. The lower end portion of the lever 15 carries a cam roll 21 which engages the edge face of a rotary cam disk 25. A tension spring 23 between the arm 11 of the bell-crank lever 3 and a post 301 on the bracket 19 holds the cam roll against the cam.

The cam 25 is secured on a shouldered portion 27 (Fig. 4) of a rotary block 29, the cam having a central bore which fits on the shouldered portion of the block. The cam 25 has also a small hole 205 which receives the reduced end portion of a spring plunger 31 slidably mounted in the rotary block 29. This plunger not only assures that the cam will be mounted in proper angular relation upon the block, but it also prevents rotation of the cam relatively to the block.

The block 29 is rotatably mounted on a flanged sleeve 33 which in turn is secured upon a stationary bushing 35. Screws 19 passing through a flange on the bushing 35 clamp the bushing to the bracket 19. The sleeve 33 is secured to the bushing 35 by a collar 39 threaded on the end portion of the bushing 35 to clamp the sleeve 33 against the flange of the bushing 35. The block 29 is prevented from moving axially on the sleeve 33 by engagement at one end with the flange on the bushing 35 and by engagement at the other end with a flange 41 formed on the sleeve 33. Mounted upon the collar 39 and secured thereupon by a bayonet coupling comprising pins 45 is a collar 43. The pins 45 are secured in the collar 43 and engage grooves in the collar 39. When the collar 43 is thus secured by the bayonet coupling its end bears against the front face of the cam 25 and holds the cam on the shouldered portion 27 of the rotary block 29. The cam may readily be withdrawn from the block 29 by twisting the collar 43 and drawing it from the collar 39. Another cam having different characteristics may then be placed on the shouldered portion of the block and secured by the collar 43.

The rotary block 29 is provided with gear teeth 47 which mesh with a pinion 49 secured on a horizontal counter shaft 51 which is rotatably mounted in bearings on the bracket 19. The counter shaft 51 also has secured on it a gear 53 which meshes with a pinion 55 secured on a horizontal driving shaft 57 which is rotatably mounted in the bushing 35.

The pinion 55 is slidably keyed on a reduced rear portion of the driving shaft 57. The forward end, i. e., the left-hand end as viewed in Fig. 4, of the pinion 55 is held against a shoulder 59 on the driving shaft by a clamping sleeve 61 rotatable with the driving shaft and movable axially thereupon. A rear end portion, i. e., left as viewed in Fig. 4, of the clamping sleeve 61 is mounted in a sleeve 63 which rotates in an adjustable bushing 65 externally threaded for axial adjustment into the bracket 19.

Slidably mounted on the sleeve 61 is a clutch member 67 which carries upon its front face a leather friction ring 69. Forward movement of the clutch member serves to bring the friction ring into engagement with a braking surface 71 on the bracket 19 to stop rotation of the drive shaft 57. The clutch member 67 also has formed on it an external conical clutch face, which upon rearward movement of the clutch member engages an internal conical clutch face 73 formed on a pulley 75 driven by any suitable source of power. The pulley 75 is mounted upon a bushing 77 which is rotatably mounted on the clamping sleeve 61. The pulley 75 is prevented from endwise movement in one direction on the clamping sleeve 61 by a flange 79 formed on the sleeve 61, and in the opposite direction by a washer 81 which is held against a shoulder 83 on the clamping sleeve 61 by the forward end of the sleeve 63. A flange 85 formed on the rear end of the sleeve 63 engages the rear end of the adjustable bushing 65. The adjustable bushing 65 has formed on its rear end

portion a flange 87 in which are provided recesses for engagement with a wrench to enable the adjustable bushing to be rotated for adjustment. A locknut 89 threaded upon the adjustable bushing 65 between the flange 87 and the bracket 19 holds the bushing 65 in adjusted position. The length of the adjustable bushing 65 is only slightly less than the distance between the front end face of the sleeve 63 and the flange 85 on the sleeve bearing, just enough to provide running clearance for the washer 81 and the flange 85. Hence if the bushing 65 is adjusted forwardly, the clutch face 73 on the pulley 75 will be adjusted forwardly toward the external conical clutch face on the clutch member 67 and the distance apart of the two clutch faces will therefore be reduced. As will hereinafter appear, the clutch member 67 is moved by a spring into engagement with the pulley to cause the drive shaft 57 to be driven, and is positively moved into engagement with the brake face 71 to stop the rotation of the driving shaft 57. The distance apart of the braking face 71 on the bracket 19 and the friction ring 69 on the clutch member 67 may therefore be adjusted to take up wear or to vary the position in which the driving shaft is stopped, by means of the adjustable bushing 65. A nut 91 and a locknut 93 are threaded upon the rear edge portion of the driving shaft 57. The nut 91 engages the rear end face of the sleeve 63 to clamp the sleeve against the washer 81 and also to clamp the washer 81 against the shoulder 83 and to clamp the front end of the sleeve 61 against the pinion 55, and the pinion 55 against the shoulder 59. The driving shaft 57, the sleeve 61, the washer 81 and the sleeve 63 are thus all clamped together by the nut 91. Not only do these parts all rotate together but they also move axially together upon adjustment of the bushing 65. The width of the gear teeth on the gear 53 and the pinion 55 is sufficient to accommodate such slight movements of the pinion 55.

The driving shaft 57 is bored axially to accommodate a rod 95 which is slidably mounted in the bore and which projects rearwardly from the driving shaft. Secured in the forward end portion of the rod 95 and extending diametrically therefrom is a pin 97. Elongated openings are provided in the drive shaft 57 and in the clamping sleeve 61 to accommodate movement of the pin in the direction of the axis of the shaft. These openings are no wider than the pin itself except for reasonable clearance and the rotary movement of the driving shaft is therefore communicated to the pin. The outer ends of the pin engage openings in the clutch member 67 which is thus slidably keyed upon the clamping sleeve 61 and the driving shaft 57. It is evident that forward axial movement of the rod 95 will move the clutch member 67 into engagement with the braking face 71 on the bracket 19, and that rearward axial movement of the rod 95 will move the clutch member 67 into clutching engagement with the pulley 75. Housed within the forward end portion of the bore in the driving shaft 57 is a compression spring 99, one end of which engages the forward end of the rod 95. The opposite end of the spring 99 engages a screw 101 adjustably threaded into the forward end portion of the bore. The spring 99 tends to move the clutch member 67 into driving engagement with the pulley 75 to cause the driving shaft 57 to be driven.

The rear rounded end of the rod 95 engages the forward end of a horizontal abutment screw 103 threaded for adjustment through a clutch lever 105 which is pivotally mounted on a hori-

zontal stud 107, carried by the bracket 19. Forward movement of the lever 105, which is effected by means later to be described, causes the screw 103 to move the rod 95 forwardly thereby causing the pin 97 to move the clutch member 67 into engagement with the braking face 71 on the bracket 19 to stop rotation of the driving shaft 57.

Extending downwardly from the lever 105 is an arm 109 to which is connected one end of a tension spring 111. The opposite end of the spring 111 is connected to a hook on the bracket 19. The spring 111 tends to move the clutch lever 105 and therefore, the screw 103 away from the rod 95. Movement of the clutch lever 105 by the tension spring 111 is limited by a horizontal link 113 adjustable in length and pivoted to the bracket 19 at its forward end. Formed in a rear end portion of the link 113 is a slot 115 which is engaged by a pin 117 in the upper end portion of the clutch lever 105.

Pivotedly connected to the upper end of the clutch lever 105 is a forwardly extending rod 119 having its forward end pivotedly connected to a more or less vertical clutch controlling arm 121. The lower end of the arm 121 is pivotedly mounted on a horizontal spindle 123 secured in the bracket 19. Secured upon the rear face of the clutch controlling arm 121 is a hardened block 125. The portion of the arm 121 above the block 125 is in the form of a yoke and embraces a clutch-release arm 127 which is pivotedly connected at its forward end by a horizontal pin 129 to the upper portion of a clutch opening lever 131. The clutch-release arm 127 has secured upon its under face a hardened block 133. When the clutch is open and the brake is applied, the forward edge face of the block 133 is in engagement with the rear face of the block 125 on the clutch controlling arm 121. The clutch opening lever 131 is more or less vertical and is pivoted about mid-way of its length on a horizontal spindle 135, secured in the bracket 19. The clutch-release arm 127 is urged downwardly and the upper end of the clutch opening lever 131 is urged rearwardly by a tension spring 137 interposed between the clutch-release arm 127 and the bracket 19.

Formed upon the lower end portion of the clutch opening lever 131 is a wedge face 139 which is so arranged as to be engaged by a pin 141 secured in the rotary block 29 on which the cam 25 is mounted. Rotation of the block 29 thus brings the pin 141 into engagement with the wedge face 139. When the clutch is closed and the driving shaft 57 is rotating, the pin 141 as it travels along the wedge face 139 pushes the lower end of the clutch opening lever rearwardly and causes the upper end of the lever to swing forwardly. Such forward movement of the lever 131 causes the clutch-release arm 127 also to move forwardly and the block 133, therefore, through its engagement with the block 125 causes the clutch controlling arm 121 to move forwardly and through the rod 119 to swing the clutch lever 105 forwardly. Such movement of the clutch lever through the rod 95 causes the clutch member 67 to move out of engagement with the pulley 75 and into engagement with the braking face 71 to stop rotation of the driving shaft 57.

To enable the operator to close the clutch at will, there is provided a hand lever 143 (Figs. 1 and 4) which is pivoted on a horizontal shaft 145 rotatably mounted in a portion 147 of the

bracket 19. The hand lever 143 has a forwardly extending arm 149 which may be depressed by the operator's finger and it has also a rearwardly extending arm 151 (Fig. 4) with the rear end portion of which a latch 153 is pivotally connected by a pin 155. The arm 149 of the hand lever is normally held up in a stop position by a spring 391. The upper end of the latch 153 lies, when the driving shaft is stationary and the clutch member 67 is in braking position, beneath the rear end portion of the clutch-release arm 127. The latch 153 is urged forwardly against a block 159 by a spring 157, the block 159 being adjustably mounted on the rod 119. When the operator depresses the arm 149 of the hand lever 143, the latch 153 is raised and moves the clutch-release arm 127 upwardly thus disengaging the block 133 from the block 125 and allowing the clutch controlling arm 121 and the clutch lever 105 to be moved rearwardly, i.e. to the right as viewed in Fig. 4, by the spring 111. Such movement of the clutch lever 105 enables the rod 95 under the influence of the spring 99 to move rearwardly, thereby moving the clutch member 67 away from the braking face 71 and into driving engagement with the pulley 75 to cause the driving shaft 57 to be driven. As the clutch controlling arm 121 moves rearwardly, the block 125 will move beneath the block 133, and the block 159 carried by the rod 119 will move the latch 153 rearwardly from beneath the clutch-release arm 127. The lower end of the clutch opening lever 131 is held rearwardly by the pin 141 until the driving shaft 57 begins to rotate. Just after such rotation of the driving shaft 57 has begun, the pin 141 will be carried away from the wedge face 139, and the spring 137 will move the upper end of the clutch opening lever 131 and the clutch-releasing arm 127 rearwardly. The block 133 is thus enabled to move down behind the block 125 in readiness to open the clutch when the pin 141 in the course of its rotary movement again engages the wedge face 139.

The hand lever 143 may be released by the operator immediately after he has started rotation of the driving shaft 57, in which case the upper end of the latch 153 (which has been pushed rearwardly from under the arm 127 by the block 159) will be lowered to below the level of the arm 127. Then the arm 127, in its rearward movement, will move over the top of the latch 153; and when the arm 127 later moves forward to stop the drive, the block 159 on the rod 119 will also move forward and permit the latch 153 to move forward until both the arm 127 and the latch 153 come to rest in their forward positions with the latch 153 under the arm 127 in readiness to release the clutch again. However, if the operator should hold the hand lever 143 depressed until the driving shaft has been stopped, the latch will then, when the hand lever is released, be moved down and will snap under the rear end portion of the clutch-release arm 127.

As has already been mentioned, the pin 141 is mounted in the rotary block 29. Five other pins 161 (Fig. 4) also are carried by the rotary block 29. The pins 161 are similar to the pins 141 except that they are slidably mounted in the block 129 for movement in a direction parallel to the axis of the drive shaft. Each of the pins 161 is engageable with the wedge face 139 in the same way as the pin 141 for causing the clutch to be opened and the driving shaft to be stopped. The pins 141 and 161 are all equally spaced angularly

about the axis of the rotary block and, if all five sliding pins 161 are in operation, the driving shaft will be stopped after every $\frac{1}{6}$ of a revolution of the rotary block. It will be understood that the cam 25 will control the movements of the edge gage in accordance with its peripheral contour and that the cam may readily be removed and similar cams of different designs secured on the rotary block 29 in its place. The design of each cam and the number of its stopping positions will depend upon the desired positions of the edge gage relatively to the channeling knives and also upon the number of changes in the position of the edge gage during the operation. The sliding pins 161, or some of them in the rotary block 29, are arranged to be held in a rearwardly extended position by abutting engagement with the face of the cam 25. When in this position the pins will be operable to engage the wedge face 139 on the clutch opening lever 131 to cause the driving shaft to be stopped. Each of the pins 161 carries a transverse pin 311, the extending ends of which engage a recess in the frame 119 to limit rearward movement of the pin 161. When the forward end of the pin 161 is against the cam 25, the transverse pin 311 will be substantially against the base of the above-mentioned recess, and the pin 161 will thus be held against longitudinal movement. If it is desired to change the position of the edge gage six times during the channeling of an insole all the sliding pins 161 will be held in their operating positions by the cam, but if it should be desired to change the position only four times, the cam then selected would have in it two holes 210 arranged to be in line with two of the sliding pins to allow these pins to be pushed forwardly by the wedge face 139 without effecting the opening of the clutch. The holes in the cam thus render the pins in line with them inoperative. The peripheral edge of the cam selected for this purpose will be so shaped as to cause only four changes in the position of the edge gage during a complete rotation of the cam. It will be understood that a number of differently shaped cams may be provided for use in a single machine, and that these cams may have openings in them to receive some of the sliding pins, the number of openings depending upon the desired number of stopping positions of the cam.

If, for example, a channeling machine equipped with the mechanism above described is to be used for operation upon an insole for a welt shoe in which it is desired that the width of the feather i. e. the portion of the face of the insole between the channel lip and the edge of the sole, shall be $\frac{1}{8}$ " along both sides of the shank portion of the insole, $\frac{3}{2}$ " along both sides of the forepart as far as the toe portion, and $\frac{1}{8}$ " around the toe, then the cam selected for this operation will have two openings to allow two of the sliding pins in the block to move forwardly when they engage the edge face on the clutch opening lever. The other three slide pins 161 and the pin 141 will be effective to stop rotation of the driving shaft when they engage the wedge face 139 on the clutch opening lever 131.

When the operator begins the channeling of such an insole along the shank portion at one side of the sole, the cam will be in its initial stopped position with the pin 141 in engagement with the wedge face 139. When in this position the portion of the cam which is engaged by the cam roll 21 will be so designed as to cause the edge gage to position the sole relatively to the channel knives in such a manner as to cause the feather

to be $\frac{1}{8}$ " wide. The operator will begin the channeling along the shank, and as the channeling approaches the forepart, he will depress the hand lever 143 and thus cause the cam to be rotated.

5 The hand lever 143 operates to start rotation of the cam by raising the clutch-release arm 127 and thereby freeing the clutch controlling arm 121. The lever 165 is thus released to the action of the spring 111 which swings it in a clockwise direction, as viewed in Fig. 4. The resulting rearward movement of the abutment screw 103 permits the rod 95 to move rearwardly under the influence of the spring 99; and the rod 95 carries the pin 97 rearwardly to bring the clutch element 67 into engagement with the rotating pulley 75. The clutch element 67 now begins to rotate; and it drives the shaft 57 through the pin 97. The shaft 57, through gears 55, 53, 49 and 47, drives the rotary block 29 upon which is secured the cam 25. Rotation of the cam 25 will operate the lever 15 which, through the link 13, will operate the bell crank 3 to shift the edge gage 1.

20 During the rotation of the cam, which will be stopped by the first sliding pin 161, the edge gage will be moved forwardly and held in forward position while the channeling proceeds along the forepart, the position of the edge gage causing the feather to be $\frac{3}{2}$ " wide. As the channeling approaches the toe, the operator will again 25 depress the hand lever 143 and thereby cause the cam to be rotated until it is stopped by the second sliding pin 161. During this portion of the rotation of the cam the edge gage is moved rearwardly and held in such a position by the cam that 30 during the channeling around the toe, the feather will be $\frac{1}{8}$ " wide. As the forepart of the other side of the sole is approached the operator again 35 depresses the hand lever 143 and thereby causes the cam to rotate until it is stopped by the third 40 sliding pin 161. During this part of the rotation of the cam the edge gage is moved forwardly into such a position that the width of the feather along the forepart is $\frac{3}{2}$ ". Finally as the channeling approaches the shank the operator again 45 depresses the hand lever 143 and the cam is rotated until it is stopped by the pin 141. During this part of the rotation of the cam, the edge gage is moved rearwardly and is so positioned that the width of the feather along the shank is $\frac{1}{8}$ ". The 50 cam is then in position for the beginning of the channeling of another insole which is to be channeled in a similar manner.

55 Each cam, as has already been mentioned, has a hole for engagement with the spring plunger 31 to assure the proper position of rotation relatively to the block 29. Each cam also will have on it a zero mark which, when the cam is placed on the rotary block with the spring plunger 31 properly orienting the cam and with the pin 141 engaging the wedge face 139 to hold the clutch open, 60 will be close to the cam roll 21.

65 The time during which the edge gage is being moved forwardly or rearwardly to vary the width of the feather depends upon the shape of the cam, and the change from one width of feather to another width may be gradual or rapid. The parts of each cam which effect the change in the 70 position of the edge gage are indicated by arcuate lines on the cam concentric with the axis of the cam. The remaining portions of the periphery of the cam are cylindrical so that although the cam is rotating to its next stopping position, no movement forwardly or rearwardly of the edge gage will take place.

75 The desired width of the feather on some in-

soles may be different at opposite sides of the shank, and in such cases the width of the feather at the inner and outer sides of insoles for right and left shoes will be the same. For example, it may be required that the width of the feather at the inner side of the shank of each insole is to be $\frac{5}{8}$ ", the width along the inner sides of the forepart $\frac{1}{16}$ ", along the outer side of the forepart $\frac{1}{4}$ " and along the outer side of the shank $\frac{5}{16}$ ". When beginning the channeling of a right insole, as above described, the edge gage must be so positioned by the cam that the width of the feather is $\frac{5}{8}$ ", it being understood that the channeling usually begins in the shank and travels in the same direction around the forepart, whether the insole is for a right shoe or a left shoe. In channeling the left insole, the feather at the beginning of the operation, must be $\frac{5}{16}$ " wide. In such a case instead of using two cams, one for a right insole and the other for a left insole, the same cam may be used. However, this cam must be removed from the rotary block and replaced in an inverted or reversed position upon changing from a series of right insoles to a series of left and vice versa. Both sides of the cam are provided with a zero mark and with a hole suitably arranged for engagement with a spring plunger 31.

When it is desired to produce a feather which is wider at one side of the shank than at the other side, the edge gage will occupy one position at the beginning of the operation and another position at the end of the operation. It is, therefore, necessary to move the cam to its starting or zero position after one insole is taken out of the machine and before another insole is presented thereto. To relieve the operator of the necessity of rememberring to trip the clutch for the purpose of causing the cam to move to its starting position, the illustrated mechanism is provided with means for tripping the clutch automatically when a work support 163 (Figs. 1 and 6) is depressed to enable the work to be removed from the machine. For this purpose, the hand lever 143 has another forwardly extending substantially horizontal arm 165 (Figs. 4, 5 and 6), the forward end portion of which has slidably mounted in it a spring plunger 167 in which is formed a recess 310 to receive the upper end portion of a rod 169. Secured upon the arm 165 is a plate 171 arranged to limit forward movement of the plunger 167 by engagement with a shoulder on the plunger. Formed upon the upper end portion of the rod 169 is a hook 173 arranged to engage the upper face of the plunger adjacent to the inner end of the recess 310 to cause the clutch to be closed when the rod 169 is moved downwardly. The lower end portion of the rod 169 is pivotally connected to an arm 175 which is secured to a shaft 177, rotatably mounted in the machine frame. Another arm 179 secured to the shaft 177, is connected by a link 181 to a vertical link 183 (corresponding to the link 41 of U. S. Letters Patent No. 984,773 granted February 21, 1911 upon the application of William C. Meyer) pivotally mounted for free swinging movement upon a stationary pin 320. The work support 163 is carried upon the upper end of a slide 322 which is movable heightwise in a guideway formed in the machine frame. The lower portion of the slide 322 carries a pin 324 upon which is pivotally mounted one arm of a bell crank 326. A pin 328, carried by the link 183, provides a fulcrum for the bell crank. A treadle rod 330, connected to the other arm of the bell crank, rocks the bell crank to depress the slide 322 against the tension of a spring

332 which normally holds the slide up to maintain the work table in its operating position.

Secured upon the rear face of the cam 25 is a rounded member 200 engageable with the rod 169. When the cam 25 is in its last stopping position (as shown in Figs. 3 and 6) before initial position, the rounded member 200 holds the rod 169 far enough within the recess in the plunger 167 for the hook 173 to engage the plunger. A tension spring 185 tends to swing the rod 169 forwardly, but is prevented from doing so by the rounded member 200. Now, when the work table is lowered for the removal of a work piece and the insertion of a new work piece, the hook 173 will trip the clutch in the manner already described, and the cam 25 will be rotated into its initial or zero position. Such rotation of the cam 25 will carry the rounded member 200 away from the rod 169. The tension spring 185 will thereupon swing the rod 169 forwardly into engagement with a stop 201, such movement of the rod serving to carry the hook 173 out of operative relation to the plunger 167. The stop 201 prevents the rod 169 from entirely leaving the recess in the plunger 167, and also from striking the cam 25. The rod 169 will remain in this inoperative position until movement of the cam into said last stopping position will cause the rounded projection 200 to engage the rod 169 and move the rod rearwardly into operative position. If the cam is intended to be used also in reversed position, it will carry a rounded projection 200 upon each face.

Having thus described our invention, what we claim as new and desire to secure by Letters Patent of the United States is:

1. In a machine for operating on soles, a support for a sole to be operated upon, an edge gage for the sole, means for moving said sole support to accommodate the removal of a sole from and the presentation of a new sole to the operating instrumentalities of the machine, operator-controlled means for shifting the edge gage from an initial position to vary the locality of the operation in relation to the edge of the sole, and means controlled by said sole-support moving means for returning the edge gage to said initial position when the sole-support moving means is operated to accommodate the removal of a sole from and the presentation of a new sole to the operating instrumentalities of the machine.

2. In a machine for operating on soles, a sole support yieldingly held up in an operating position, an edge gage for the sole, mechanism for lowering the sole support to accommodate the removal of a sole from and the presentation of a new sole to the operating instrumentalities of the machine, power driven means for shifting the edge gage from an initial position to vary the locality of operation in relation to the edge of the sole, operator-controlled means for actuating said power driven means to shift the edge gage from initial position, and means operated by said mechanism for actuating said power driven means to return the edge gage to initial position upon the lowering of the sole support.

3. In a machine for operating on soles, an edge gage for a sole, a normally stationary cam, mechanism controlled by said cam for determining the position of said edge gage, means for driving said cam to vary the position of said gage, operator-controlled means for starting the drive of said cam, and means controlled by said cam for stopping the drive of the cam.

4. In a machine for operating on soles, an edge gage for a sole, a rotary cam, mechanism con-

trolled by said cam for determining the position of said edge gage, means for driving the cam to vary the position of the gage, means for starting the drive of the cam, means for stopping the drive of the cam, and means carried by said cam for actuating said stopping means at a desired position of rotation of said cam.

5. In a machine for operating on soles, an edge gage for a sole, a normally stationary replaceable rotary cam, mechanism controlled by said cam for determining the position of said edge gage, means for driving said cam, operator-controlled means for starting the drive of said cam, and means operable after the drive of the cam has been started to stop the drive at one of a plurality of control positions, said replaceable cam being constructed and arranged to engage said stopping means selectively to cause the drive to stop only at the control positions desired for that particular cam.

6. In a machine for operating on soles, an edge gage for a sole, a normally stationary rotary cam, a rotary member upon which said cam is replaceably mounted, mechanism controlled by said cam for determining the position of said edge gage, means for driving said rotary member, a clutch for coupling and uncoupling said driving means to said rotary member, operator-controlled means for coupling said clutch, mechanism for uncoupling said clutch, and a plurality of pins angularly spaced around the axis of the cam and slidably mounted in guideways in said rotary member for movement in a direction parallel to the axis of the cam, each of said pins when held in an extended position in its guideway by abutting the face of the cam being engageable with the unclutching mechanism to stop the rotation of the cam in a predetermined position, said replaceable cam being one of a series of cams having different characteristics, and each cam having holes in its face to enable one or more of the pins to slide from extended to inoperative position, thereby selectively determining the stopping positions of that particular cam.

7. In a machine for operating on soles, an edge gage for a sole, mechanism for positioning said edge gage, a shaft, operator-controlled means for coupling said shaft to a source of power, mechanism for uncoupling the shaft, a cam for controlling said edge-gage-positioning mechanism and also for controlling said uncoupling mechanism, said cam being one of a series of interchangeable cams of different characteristics, and means for readily and interchangeably securing said cam on said shaft in operative relation to said positioning and said uncoupling mechanisms to effect a desired positioning of the edge gage and to uncouple the shaft from the source of power a desired number of times for a single rotation of the cam.

8. In a machine for operating on soles, an edge gage for a sole, a normally stationary rotary cam, mechanism controlled by said cam for determining the position of said edge gage, a hollow drive shaft, driving connections between said shaft and said cam, a driven friction clutch member slidably mounted on said shaft, a clutch operating rod slidably mounted within said shaft, a pin connecting said rod to said clutch member for operating the clutch member, said hollow drive shaft having a longitudinal slot to accommodate operating movements of the pin while preventing rotation of the clutch member relative to the drive shaft, a driving clutch member engaged by said driven clutch member to start rotation of the cam when the driven clutch member is moved axially in one direction, a brake engaged by said driven clutch member to stop rotation of the cam when the driven clutch member is moved axially in the opposite direction, yieldable means for urging said driven clutch member into driving position, means engageable with said clutch rod for positively holding the driven clutch member in braking position, and means for controlling said holding means to start and stop rotation of the cam.
